CLAIM

The ornamental design for a drinking cup, as shown and described.

DESCRIPTION

FIG. 1 is a perspective view of a drinking cup showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a perspective view of the drinking cup of FIG. 1, shown with straw folded in an alternate configuration of use. The broken lines depict portions of the drinking cup that form no part of the claimed design.

1 Claim, 9 Drawing Sheets
